DESIGN FOR A TOOL BAG APRON

Florabelle R. Stewart, Portland, Oreg.

Application March 7, 1945, Serial No. 118,314

Term of patent 7 years

(Cl. D3—26)

To all whom it may concern:

Be it known that I, Florabelle R. Stewart, a citizen of the United States of America, residing at Portland, county of Multnomah, and State of Oregon, have invented a new, original, and ornamental Design for a Tool Bag Apron, of which the following is a specification, reference being had to the accompanying drawing, forming a part thereof wherein:

I claim:

The ornamental design for a tool bag apron, as shown.

FLORABELLE R. STEWART.
